UNITED STATES PATENT OFFICE

WHILEY THOMAS BURNES, OF MEMPHIS, TENNESSEE

DESIGN FOR A CANE OR SIMILAR ARTICLE

Application filed October 26, 1929. Serial No. 33,172. Term of patent 7 years.

To all whom it may concern:

Be it known that I, WHILEY THOMAS BURNES, a citizen of the United States, residing at Memphis, in the county of Shelby and State of Tennessee, have invented a new, original, and ornamental Design for Cane or Similar Article, of which the following is a specification, reference being had to the accompanying drawing, forming part thereof.

I claim:

The ornamental design for a cane or similar article as shown.

WHILEY T. BURNES.
